(57) **CLAIM**

The ornamental design for a side appearance of a contour chair, as shown and described.

DESCRIPTION

FIG. 1 is a side view of a contour chair embodying the present invention and oriented in a first position.

FIG. 2 is a side view of the contour chair shown in FIG. 1 oriented in a second position; and,

FIG. 3 is a side view of the contour chair shown in FIG. 1 oriented in a third position.

The broken lines showing of the screw and the bracket in the drawing are for illustrative purposes only and form no part of the claimed design.
